UNITED STATES PATENT OFFICE

110,427

DESIGN FOR A SHOE OR SIMILAR ARTICLE

Benjamin Benjamin, Freeport, N. Y.

Application June 13, 1938, Serial No. 77,785

Term of patent 3½ years

To all whom it may concern:

Be it known that I, Benjamin Benjamin, a citizen of the United States, residing in Freeport, in Nassau County, and in the State of New York, have invented a new, original, and ornamental Design for a Shoe or Similar Article, of which the following is a specification, reference being had to the accompanying drawing, forming part thereof:

In the drawing:

I claim:

The ornamental design for a shoe or similar article, substantially as shown.

BENJAMIN BENJAMIN.
